COAL MINING APPARATUS

Filed Oct. 24, 1921

2 Sheets-Sheet 2

UNITED STATES PATENT OFFICE.

EDMUND C. MORGAN, OF NEW YORK, N. Y.; OLIVE EUGENIE MORGAN EXECUTRIX OF
SAID EDMUND C. MORGAN, DECEASED.

COAL-MINING APPARATUS.

Application filed October 24, 1921. Serial No. 509,978.

My invention relates to an improved system of mining coal and its object is to provide means for acting on a semi-solid mass of coal at a mine wall after being severed from a mine vein, to tear apart and spread out the coal to facilitate the action of a loading machine thereon.

More particularly it is the object of the present invention to provide a plurality of spaced-apart haulage devices adapted to be spread apart in an under kerf in position to act on the coal after being severed from a mine vein by blasting or otherwise, in order that the semi-solid mass of coal may be torn apart and spread out to facilitate the handling thereof for the purpose of loading into mine cars.

Another object of the invention is the provision of blasting means combined with hauling mechanism which can be located below the mass of coal broken down and used to tear apart and spread out the severed mass of coal to facilitate the loading thereof.

Other objects of the invention will appear hereinafter, the novel features and combinations being set forth in the appended claims.

In the drawings—

Fig. 1 is an elevational view of one of my improved haulage devices inserted into an under kerf at the base of a mine wall prior to the severing of the coal from a mine vein;

Fig. 2 is an elevational view of the haulage mechanism and the means for operating the same after the coal has been severed from a mine vein by a blasting operation;

Fig. 3 is an elevational view illustrating the tearing apart and spreading out of the coal after it has been severed and after the haulage mechanism has been operated;

Fig. 4 is a plan view of the structure shown in Fig. 2;

Fig. 5 is a sectional elevation of a modified haulage device with blasting mechanism combined therewith; and

Fig. 6 is a sectional view taken as indicated by the arrow 6 in Fig. 5.

By referring to Fig. 2 of the accompanying drawings it will be seen that a flat elongated plate 7 is provided with a hook 8 at one end extending upwardly and an eye 9 at the other end for attachment thereof of a rope 10. The rear end of the rope 10 is provided with an eye 11 for receiving a hook 12 at the free end of the rope 13 which is

adapted to be wound on a winding drum 14. As shown in Figs. 2 and 4, the winding drum 14 is mounted on a shaft 15 journaled to a wheeled truck 16 which is adapted to travel on the mine track 17. A motor 18 is connected by the gearing 19 to the shaft 15 to operate the rope drum 14. A similar rope drum 20 may be located on the opposite side of the truck 16, as shown in Fig. 4, and this rope drum 20 connected to the motor 18 for operation thereby at the same time that the rope drum 14 is rotated.

By referring to Fig. 4 it will be seen that the rear ends of the elongated haulage devices 21, 22 and 23 may be provided with hooks 24, 25, 26 and 27 so that the eyes 28, 29, 30 and 31 of the ropes 10', 32, 33 and 34 may be readily connected or disconnected to the haulage devices whenever desired. The rear ends of the ropes 10', 32, 33 and 34 are respectively provided with eyes adapted to be connected to the hooks 12, 35, 36 and 37, the latter being connected to the free ends of the ropes 13, 38, 39 and 40. It will thus be seen that the ropes 13 and 38 are wound on the drum 14, and the ropes 39 and 40 are wound on the drum 20. The ropes 13, 38, 39 and 40 extend to the under sides of the drums 14 and 20 so that when the drums are rotated in a clockwise direction, as viewed in Fig. 2, pulls will be exerted simultaneously on all of the ropes to operate the coal spreaders.

After an under kerf, as shown at 41 in Fig. 1, has been cut beneath the mass of coal to be dislodged, the elongated hooked haulage devices may be located in this kerf in spread-apart relation, as illustrated in Fig. 4. The blasting holes, one of which is illustrated at 42 in Fig. 1, and may be also arranged in spread-apart relation, one above each of the elongated haulage spreaders. While the latter remain in the under kerf the blasting operations are carried out to dislodge the coal. It often occurs in practice that coal is dislodged by blasting operations in a semi-solid mass which is difficult to load into mine cars, and in fact in some cases impossible for the loading machine to handle efficiently. While the coal is severed from the mine vein by the blasting operations it tends to remain packed so tightly that it is difficult, if not impossible, to remove the severed mass of coal without considerable additional labor.

However, by means of the plurality of spaced-apart individual hooked haulage devices shown in the accompanying drawings the semi-solid or packed mass of coal shown at 5 43 in Fig. 2 may be loosened, torn apart and spread out, as shown at 44 in Fig. 3. This is effected by operating the rope drums 14 and 20 to exert pulls on the ropes or cables which are connected between the rope drums and the 10 individual haulage spreaders.

In order to anchor the truck so that it will act as an abutment during the operation of the rope drums I have shown a roof jack 45 pivotally connected at 46 to the top of the 15 truck and comprising a screw-threaded rod 47 and operating wheel 48 and a roof-engaging shoe 49. By mounting the roof jack in an inclined position, as shown in Figs. 2 and 3, and causing the shoe 49 to engage the roof 20 by operating the wheel 48 any tendency of the truck to move forward during the operation of the spreaders will be resisted by the roof jack.

In Fig. 5 I have shown a modification of the 25 system of tearing apart and spreading the coal by providing a horizontal kerf along the roof at 50 so that the coal when blasted may spread upwardly to a limited extent. The blasting holes 51 are located at the base of the 30 mine wall to receive the blasting mechanism comprising a rod or tube 52 provided with an eye 9' for receiving the haulage rope 10. The rod or tube 52 has extending therethrough a pair of insulated wires 53, 54 which terminate 35 at their inner end in a charge of blasting powder 55. The blasting powder may be wrapped in a paper container 56 which is held in a pocket 57 at the end of the blasting bar 52. The pocket 57 is provided with an 40 annular shoulder against which rests a ring or washer 58 of resilient material, such as rubber.

Surrounding the rod 52 is a sleeve 59 which is provided with a conical wedge 60 adapted 45 to extend into the ring or washer 58 which acts as an abutment to confine the blasting charge 55, 56. The sleeve 59 is provided with a collar 61 back of the conical wedge 60 so as to hold the split serrated ring 62 against 50 the rubber washer 58. By referring to Fig. 6 it will be seen that the ring 62 is provided with circular serrations 64, and Fig. 5 shows these serrations inclined rearwardly. As 55 shown at 63 in Fig. 6 a slot extends longitudinally of the ring 62.

The rear end of the rod 52 is screw-threaded at 65 to receive a nut 66 for operation by the wheel 67. The nut 66 bears against the rear end of the sleeve 59 so that when the wheel 67 60 is rotated in the proper direction the conical wedge 60 will be moved toward the shoulder 57. When this occurs the split ring 62 is spaced from the collar 61, but when the rubber ring 58 engages the shoulder 57 further 65 forward movement of the split ring 62 will be

resisted by the ring 58. Therefore, when the wheel 67 is continued in its rotation the conical wedge 60 will spread apart the split ring 62, forcing the serrations into the walls of the cylindrical blast hole 51. At the same time 70 the rubber ring 58 will be spread radially by the conical wedge 60 into contact with the cylindrical wall of the blast hole 51 to form an air-tight joint.

In the system shown in Figs. 5 and 6 the 75 coal is overcut, which may be done by means of an arc wall machine, and also drilled for blast holes at the floor so that blasting may be effected upwardly and outwardly. After the overcut has been made and the blasting holes 80 drilled, a plurality of blasting bars carrying blasting charges may be placed in the blast holes. By operating the wheel 67 of each 85 blasting bar from a position outside of the blast hole an air-tight joint at the rubber rings is obtained and the serrated split rings firmly anchor the blasting bars to resist their being thrown backwardly. The clamping mechanism comprising a split ring 62 therefore 90 affords an effective tamping for the blasting charge. By connecting suitable blasting apparatus for producing a jump spark, to the electric terminals 53 and 54 the coal may be blasted down while the blasting bars remain 95 buried under the semi-solid mass of coal severed from the mine vein. Then upon 100 operation of the rope drums 14 and 20 shown in Fig. 4 the blasting bars may be pulled rearwardly and the collars 61 and the serrations on the split rings 62 relied on to tear apart 105 and spread out the severed coal in the manner illustrated in Fig. 3.

Obviously those skilled in the art may make 110 various changes in the details and arrangement of parts without departing from the spirit and scope of my invention as defined by the claims hereto appended and I wish therefore not to be restricted to the precise construction herein disclosed.

Having thus fully disclosed my invention 115 and illustrated an embodiment thereof, what I desire to secure by Letters Patent of the United States is:

1. A combined coal spreader and blasting bar comprising blasting mechanism carried 120 by said bar, means for securely clamping the blasting bar against the walls of a drilled hole in a mine wall, and connections for haulage mechanism to enable said blasting bar to act as a spreader after the coal has been dislodged from a mine vein.

2. In mining apparatus, the combination 125 with a blasting bar having insulated electric terminals adapted to extend to a blasting charge, of a sleeve on said bar, a conical wedge at the forward end of said sleeve, an elastic ring on said bar in position to be operated on by said wedge to form a tight fit in the blasting hole, a serrated split ring on said wedge, and means for moving said sleeve relatively to 130

said bar to operate said wedge to secure said serrated ring to the cylindrical wall of the blast hole.

3. In mining apparatus, the combination 5 with a bar adapted to be inserted into an incision in a coal vein with an explosive blasting charge carried thereby, of a sleeve on said bar, means for confining the space where the blasting charge is located, spreading mechanism mounted on said bar adjacent the blasting charge at the inner end portion of said bar, and connections for operating said bar to move the spreading mechanism and cause the latter to loosen the dislodged coal and spread it out to facilitate loading.

4. A combined coal spreader and blasting bar adapted to be inserted into an incision in a mine vein with an explosive carried by said bar, means for clamping the bar to the walls 20 of the incision to confine said explosive, and connections for mechanism to operate said bar to act as a spreader after the explosive has been set off and the coal dislodged from the mine vein.

25 5. A coal spreader comprising an elongated bar, a cylindrical sleeve on said bar, a collared conical wedge at the forward end of said sleeve surrounding the inner or forward end portion of said bar, a split cylindrical sleeve having a serrated exterior surface and having an inner surface fitting said conical wedge, and means for moving the sleeve and the said collared wedge to spread apart the split serrated sleeve to cause the serrations to 30 grip the cylindrical wall of a bore hole into which said spreader is inserted.

6. A combined mineral spreading and blasting device comprising a chemically explosive blasting charge and means for confining the same in an incision in the mine vein, means operable from the outside of said incision for clamping said confining means to the walls of said incision, and connections for operating said spreader by pulling the same 40 away from the unmined mass to loosen the dislodged mineral and spread it out to facilitate loading thereof after said explosive has been set off.

7. In mining apparatus, the combination 50 with an explosive blast charge and a blasting bar adapted to insert such charge into a blast hole in a mine vein, of an abutment for closing the space containing the blast charge, and means on the bar for locking the abutment in

predetermined position and at the same time 55 affording tamping in said hole for said blast charge.

8. In mining apparatus, the combination with an explosive blast charge and a blasting bar carrying said blast charge for insertion 60 into a blast hole in a mine vein, of an abutment to confine the blast charge, and means for clamping the bar to the walls of the blast hole to hold said abutment in place.

9. In mining apparatus, the combination 65 with a blasting bar adapted to support at its forward end an explosive blast charge for insertion into a blast hole in a mine vein, of an abutment to confine the blast charge, and means operable from the outside of said blast 70 hole while said abutment is in position to confine such charge, to clamp the bar to the walls of the blast hole and secure such abutment in its position.

10. In mining apparatus, the combination 75 with a blasting bar having a socket at its forward end to receive and carry an explosive blast charge for insertion into a blast hole in a mine vein, of an abutment on said bar in 80 position to confine said blast charge, clamping mechanism on said bar for securing the latter in the blast hole, and means for operating said clamping mechanism.

11. A combined coal spreader and blasting bar comprising electric blasting mechanism 85 carried by said bar and extending to the forward end of said bar to a blasting charge, and connections for haulage mechanism to enable said blasting bar to act as a spreader after 90 the coal has been dislodged from the mine vein by the electrical operation of the blasting charge.

12. In mining apparatus, the combination with an explosive blasting charge, of an elongated coal spreader adapted to be located in 95 an incision in which said blasting charge is placed and adjacent the latter in position to spread out coal operated on by the said blasting charge, electrical connections carried by said elongated coal spreader and extending to the blasting charge to set off the latter, and means for operating said coal spreader after 100 said blasting charge has been set off electrically.

In testimony whereof I have signed my 105 name to this specification on this 22nd day of October, A. D. 1921.

EDMUND C. MORGAN.
